AUTOMATIC LATCH MECHANISM FOR
PORTABLE EXTENSION MASTS

James Moon, Altadena, Calif., assignor to Western Oil Tool & Engineering Co. Inc., Hollydale, Calif., a corporation of California

Application November 10, 1947, Serial No. 785,165

6 Claims. (Cl. 189—14)

1

This invention relates to a latching mechanism and particularly to a latching mechanism for telescoping masts, and more particularly this invention is designed for use as a latching mechanism in the telescoping drilling mast type of derrick employed with portable oil well drilling and servicing rigs.

Portable drilling and servicing rigs are commonly employed in the petroleum production for the drilling and servicing of wells. Such rigs are usually transported on trucks or trailers which carry a mast or derrick which may be positioned on the truck and erected at the drilling site. These masts are usually composed of one or more sections, usually two, in such form that the upper section may be telescoped into the lower section when the derrick is to be transported, and upon erection of the lower section the telescoped derrick may be withdrawn or extended from the lower section to give a mast of the desired height. This type of mast for such purposes is now conventional and is described in Patent No. 2,204,713 and in my co-pending applications Serial Nos. 786,461, filed November 27, 1947 and 10,412 filed February 24, 1949.

Since such masts are called upon to carry tremendous loads on the order of 200,000 pounds, it is important that when the derrick is extended the extensible portion be securely latched in position in the lower portion.

In such derricks of the prior art, manually operable latches have been provided and a number of bad accidents have occurred because of the failure to securely latch the derrick in position prior to application of load. Additionally, the latches, heretofore used, may be accidentally damaged due to improper setting when the derrick is retracted, and upon extension of the derrick the damaged latch fails to set and failure results. Accidents due to this cause have also been known.

It is an object and feature of my invention to provide a latching mechanism which automatically latches the extensible section of the mast to the lowermost section when the extensible mast section has reached a predetermined position in relation to the lower section during the extension thereof and will hold the upper section securely in position under all loads designed to be taken by the derrick, and will also automatically unlatch and move into an inoperative position when the derrick is to be retracted and remain in that position during the retraction thereof.

It is a particular feature of this invention that the latching mechanism operates automatically

2

and without attention so that reliance is not had upon the human element in latching the derrick in position or unlatching it for retraction.

It is another feature of my invention that the loads imposed upon the derrick act to more securely latch the derrick in position.

The latching mechanism is at all times out of the way, both when in operative position and in inoperative position.

10 These and other objects of my invention will be clear from the following description taken together with the accompanying drawings, in which:

15 Fig. 1 is a vertical elevation partly fragmentary and partly schematic, showing a mast in erected position;

Fig. 2 is a fragmentary detail of one of the legs of the extensible section showing the relationship between the legs and the valve actuating mechanism in one position;

20 Fig. 2a is similar to Fig. 2, but showing the valve actuating mechanism in another position;

Fig. 3 is a schematic showing of part of the piping employed in the pneumatic actuation of

25 the latching mechanism;

Fig. 4 is a fragmentary part section taken on the line 4—4 of Fig. 1; said section also being taken on the line 4—4 of Fig. 5;

30 Fig. 5 is a fragmentary part section taken along the line 5—5 of Fig. 4;

Fig. 6 is a section taken along the line 6—6 of Fig. 7, showing in diagrammatic form the piping layout and the valve mechanism in position to move the latches into their operative position;

35 Fig. 7 is a section taken along line 7—7 of Fig. 6;

Fig. 8 is a section taken along line 8—8 of Fig. 5; and

40 Fig. 9 is a schematic view of the valve showing it in position for moving the derrick to the inoperative position.

Derrick 1 may be mounted upon truck 2 in any conventional manner, such as shown in Patent No. 2,204,713 or in my co-pending application Serial No. 786,461, where it is usually mounted upon the end of the truck, or may be mounted upon the front of the truck, as is shown in my co-pending application Ser. No. 10,412. The derrick is hingedly mounted at 3 upon a truss 4, one mounted upon each side of the truck 2, and is retracted onto the derrick or is extended around hinge 3, by an extensible jack 5 which is hingedly connected to the derrick 1 at 6 and to the truck 2 in a manner not shown. Such connection of the extensible hydraulic jack 5 for the

erection and retraction of the derrick is conventional and is shown in the aforementioned patent, and forms no part of this invention.

The derrick 1 is composed of a lower section 7 and an upper section 8 which is telescoped into section 7 when the derrick is retracted and may be extended from section 7 to an elevated position as shown in Fig. 1. Lower section 7 is separated into a number of panel sections by horizontal box girders 9a to 9f, inclusive; 9a forms the top girder of the lower section, and 9f forms the lowermost girder of the lower section. These girders connect the front legs 12 and 13 and the rear legs 10 and 11 of the lower section, as shown in Figs. 4, 6, and 7.

Mounted on the front end of each of the box girders adjacent the front legs 12 and 13 are guide channels 14 which extend between each of the adjacent box girders 9a to 9f, inclusive. These are connected to the box girders in the manner shown most clearly in Fig. 7. At each of the box girders adjacent each of the legs 10, 11, 12, and 13 is a semi-circular channel member 13' welded to the box girders and connected to the legs 10, 11, 12, and 13, respectively, by a gusset 13a. Circular guide channels 14 are connected (by welding) by spacers 15 to the channels 13' to provide a space between the channels 14 and 13' for purposes to be described hereinbelow.

The front legs of the upper telescoping section, shown at 17, are guided in the channel member 14 mounted adjacent the front legs 12, and the back legs 18 of the telescoping inner section are mounted and guided in guide channels 14 mounted adjacent the rear legs 10 and 11. The inner section is thus securely guided in the lower section and may be extended and in its extension is guided by the channels 14.

In a derrick adapted for the use of the derrick latch of my invention I prefer that at least one of the rear legs, either 10 or 11, be hollow. Of course, all may be tubular in character but at least one is provided (see Fig. 3) at its lower end close to the bottom channel 9f with a plug or diaphragm 19 which seals that end of the tubular member. Adjacent the diaphragm 19 is provided a drain outlet 20 suitably provided with a valve. The upper end of the tubular leg adjacent the member 9a is also closed by a plug or diaphragm 22, thus providing a sealed tubular conduit between 19 and 22. An inlet line 21 is connected to the tubular member at some convenient point intermediate the diaphragm 22 and 19 to be connected to a source of high pressure fluid such as oil or air for purposes to be described hereinafter.

Mounted underneath the box girder 9a is a valve 24 preferably of the rotary type and actuated by spokes 25 (see Figs. 2 and 2a) which act to rotate the four-way plug 24. These spokes are operated by a hingedly mounted dog 25' which is mounted on a bracket 26 on one of the legs 18. This dog will break at the hinge point on the descent of the leg as it contacts the spokes 25 of the valve so as not to rotate the valve, but is rigid on the upstroke of the leg so that it will rotate the valve. In this fashion the valve is rotated a quarter turn when the upper section 8 is raised sufficiently so that the dog 25' passes the valve on the upward movement of 8, but will not actuate the valve when, on the downward movement of section 8, the dog again passes by the valve.

One of the ports 59 of the four-way plug valve 24 (see Figs. 3 and 6) is connected by a conduit 28 to the pressure outlet 23 of the tubular leg 10.

Another port, shown at 61 (see Figs. 3 and 6) is connected to the conduit 29 which is in turn connected to two manifoldest pressure lines 31 and 31'. Another port 60 is connected to the line 29 and to the manifoldest lines 32 and 32', and a fourth port is connected to the atmospheric vent 63. The bores 24a and 24b of the valve 24 can make the connections shown in both Figs. 6 and 9, and a quarter turn will change the port position from one form to the other.

One of the box girders, preferably 9b, has its lower plate 62'' cut out to form an entry to the hollow chamber 59 inside the box girder between the legs 10 and 13 and also between 11 and 12. The upper plate 61' of the box girder is bored with bores 60' positioned in the top plate of 61' adjacent each of the front legs 12 and 13 and also adjacent the rear legs 10 and 11. The cut-out portions of the bottom plate 62' are covered by plates 30 which may be bolted to the bottom plate 62', as shown in Figs. 4, 5, and 6. These plates carry the latching mechanism and are similarly constructed, being right and left handed, as shown in Figs. 4, 5, and 6. Each of the plates 30 carry sleeves 38 welded to the plates 30 on brackets 39.

The sleeves 38 carry bushings 40 in which is rotatably mounted the shaft 41. Mounted on shaft 41 is a collar 42 secured to the shaft 41 by a key 41'. A spring 43 is mounted on shaft 41 between the collar 42 and cap 43'. Hingedly mounted upon the plate 30 at 30a are power cylinders 30' carrying a piston 33 connected to a piston rod 34 which is pivotally connected at 35 to a bracket 36 adjustably mounted upon a reciprocating rod 37. The rod 37 is connected, at the end of the rod 37 nearest the rear legs 10 and 11, respectively, by an arm 46 which is pivotally connected at 45 to the bracket 44 mounted upon the collar 42. The end of the rod 37, nearest the legs 12 and 13, is connected to a similar bracket 44 by the arm 47 which is pivotally connected to the bracket 44 by a pivot 45 and connected to the rod 37 by means of a sleeve 48 adjustably mounted upon rod 37 by means of the retaining nuts 49 and 50 which are screwed onto the threaded end of the rod 37.

The lower end of the shaft 41 which protrudes beneath the plate 30 is connected by an arm 51 mounted at right angles to the axis of the shaft 41. The arm 51 is connected to a cup 52 whose axis is parallel to the axis of 41. The inner diameter of the cup 52 is of such size as to receive the legs 17 and 18, as will be described below. The cup is beveled at its upper end at 53 and is closed by a split ring 54 which extends to form a ledge 55 and has a lip 57 to form a ledge 58.

The operation of the device will be clear from what has been said before. When the derrick is in position on the truck the upper section 8 is retracted completely inside the lower section 7. The bottom of the upper section is adjacent the lower girder 9f. When it is desired to erect the derrick, the hydraulic jack 5 is extended, the derrick rotating round the hinge point 3 upon the frame 4 and around the hinge point 6 on the jack 5, and the derrick is moved into erect position shown in Fig. 1. The bottom derrick section may be latched in position by conventional means usually employed in this art. The upper section 8 may then be extended by moving this section in its guideways 14 into the erect position shown in Fig. 1. Means for extending the derrick are well known and are now used in such derricks, or I may use the extending means

shown in my co-pending application Ser. No. 10,412. At this point, as well as when the derrick is retracted, the latching mechanism has the position shown in Figs. 4 and 5, with the cups underneath the plates 30 and the piston is fully extended as shown in Fig. 4.

As the derrick section 8 moves up, when one of the legs 18 carrying the bracket 26 has reached a point near its upper limit of travel, the dog 25' (see Fig. 2) will rotate the valve 24 to place it in position, shown in Fig. 6. The derrick may then move upward a short distance, the dog 25' clearing the arm 25. Pressure is thus applied via leg 10 and line 28, through port 59, bore 24b, port 60, line 29 to lines 32 and 32'. The lines 31 and 31' are vented via line 27, port 61, bore 24a, port 62, and line 63. The piston rod 34 is moved in the direction of the arrow, Fig. 6, to rotate the shaft 41 to move the cups 52 in the direction of the arcuate arrows on Fig. 4. This moves the cups from the position Fig. 4 to the position shown in Figs. 6 and 7. The derrick legs 18 and 17 have been raised so that their lower end is spaced from the top of the lower section 14 for a distance greater than the height of the cups, i. e., the distance between 53 and the bottom 58' of the ring 54. This permits the cups to swing into position with the outer rims of the ring 54 against 13. This aligns the cups axially with the legs 17 and 18, respectively. The upper section is then lowered. The dog 25' breaks at the hinge point as the arm 26 passes the valve and thus the valve is not actuated. The pressure in the cylinder thus holds the cups against the guide 13. The four legs 17 and 18 enter the corresponding cups and the weight of the derrick pushes the shaft 41 down, the shaft and key 41' sliding in the collar 42 and the keyway cut therein, compressing the spring 43. The cups are set on top of the guide 14 with the rim 58' nesting between 13 and 14. The derrick is thus locked in extended position. Each of the four cups act similarly.

Usually the derrick legs 18 are smaller in diameter than the derrick legs 17 and the cooperating cups must therefore be dimensioned to receive these derrick legs. In this position it will be observed that the legs rest directly on top of the guide section 14 which are in turn connected through the box girders to the legs 10, 11, and 12 of the lower derrick section so that the load imposed on the upper section is transmitted directly to the derrick legs and through the guide sections. It will be observed that none of this load is imposed upon the latching mechanism except in that the loads are transferred through the ring members 54 to the derrick legs. It will also be observed that the greater the load on 8, the more firmly do the legs seat in the cups and the more firmly are they latched in position.

In retracting the derrick, the reverse procedure is employed. The derrick is lifted until the bottom of the legs clears the top rim 53 sufficient to permit the spring 43 to retract the rim 58' from between 13 and 14. In so doing the dog 25' again rotates the valve 90° (see Fig. 2) moving the valve from the position shown in Fig. 6 to that in Fig. 9. The air pressure is now applied to the cylinders through lines 31 and 31', 32 and 32' being vented through 63. This causes the piston and piston rod to move to the right (Fig. 6) in the direction opposite to that indicated by the arrow. The cups are swung into the position shown in Fig. 5 by movement in a direction opposite to that of the arrows in Fig. 4. The legs may now

descend along the guideways 14 to permit the retraction of the upper derrick section.

While I have described a particular embodiment of my invention for the purpose of illustration, it should be understood that various modifications and adaptations thereof may be made within the spirit of the invention as set forth in the appended claims.

I claim:

1. An automatic latching mechanism for sectional extensible drilling masts comprising a lower section, an upper extensible section telescopically mounted in said lower section in extensible and retractile position, a latching means mounted on said sections for latching said upper and lower sections with the upper section in extended position, power actuated means for moving said latching means into operative latching position and for moving said latching means into inoperative unlatched position, automatic means mounted on said mast, said automatic means including means for controlling the direction of application of power in one direction to actuate said latching means, for moving said latching means into operative latching position, and means for operating said controlling means upon the arrival of said telescoping section at a predetermined position during the upward extension of said derrick, said controlling means being also operative to control said power means to move said latching means to inoperative unlatching position upon movement of said upper section from its extended and latched position.
2. An automatic latching mechanism for sectional extensible drilling masts comprising a lower section, an upper extensible section telescopically mounted on said lower section in extensible and retractile position, a latching means mounted on said sections for latching said upper and lower sections with the upper section in extended position, means for moving said latching means into operative latching position and for moving said latching means into inoperative unlatching position, said latching means comprising an interlock between said extensible members, a pneumatically actuated power means mounted on said mast for moving said interlock to operative latching position and also operative for moving said interlock into inoperative unlatched position, a pneumatic line connected to said power means, a valve in said line mounted on said mast, means mounted on said mast to actuate said valve to apply the pneumatic pressure in said power means to move said latching means from an unlatched to latching position upon the arrival of said telescoping section at a predetermined position during the upward extension of said telescoping section, said valve actuating means being operative also to apply pneumatic pressure in said power means to move said latching means to inoperative unlatching position for retraction of said derrick from its initial extended latched position.
3. A latching means for extensible sectional drilling masts comprising a lower section, an upper extensible section telescopically mounted in said lower section, said sections being composed of cross-braced longitudinal members, a latching mechanism for said mast comprising a plurality of cup-shaped members, said members being hingedly mounted on the cross braces of one of said members, and means for moving said cup-shaped members about said hinge point into position between the longitudinal members of the upper and lower sections in load transmitting

relationship between the longitudinal members of said section.

4. A latching means for extensible drilling masts comprising a lower section, an upper extensible section telescopically mounted in said lower section, each of said sections composed of longitudinal leg members, lateral cross bracing between said leg members, a latching means mounted on said lower section, said latching means comprising an arm hingedly mounted on a hinge point positioned on one of the cross braces on the lower section, a leg receiving member mounted on said arm, means for moving said arm about the hinge point to swing said arm into latching position underneath the lower end of one of the leg members of the upper section upon arrival of said end at a point above said leg receiving member, means mounted upon said lower section underneath said leg receiving member to engage said leg receiving member in latching position, and means for engaging in latching position said lower end of said leg of said upper section, said leg receiving member and said aforesaid means in said lower member upon lowering of said leg into said leg receiving member.

5. A latching means for extensible drilling masts comprising a lower section, an upper extensible section telescopically mounted in said lower section, each of said sections composed of longitudinal leg members, lateral cross bracing between said leg members, a latching means mounted on said lower section, said latching means comprising an arm hingedly mounted on a hinge point positioned on one of the cross braces on the lower section, a cup mounted on said arm, a pneumatic power cylinder containing a piston and a piston rod mounted on said cross bracing upon which said hinge point is mounted, a link between said piston rod and said arm, a pneumatic pressure line connected to said power cylinder, a valve in said line and mounted on one of said sections, a valve actuating means mount-

- ed on the other section and acting to actuate said valve upon the arrival of said upper section at a predetermined location on extension thereof, said hinged arm being of length sufficient to move said cup underneath the end of a leg of said upper section upon arrival of said upper section at said predetermined location during the extension thereof, a cup receiving means mounted upon said lower section underneath said cup when positioned to receive the end of the leg of the upper section, and means for engaging in latching position said lower end of said leg, said cup and said cup receiving means upon lowering of said leg into said cup.
6. An automatic latching mechanism for sectional drilling masts, comprising a lower section, an upper extensible section, telescopically mounted in said lower section in extensible and retractile position, a latch means mounted on one of said sections for latching said upper section in extended position against retractive movement of said extensible section, means mounted on said mast for actuating said latching means to move said latching means into a latched position to prevent the retraction of said extensible section, actuating means for moving said latching means into an unlatched position to permit the retraction of said extensible section, said actuating means being actuatable by the arrival of said extensible section at a predetermined position during said extension of said extensible section to cause the latching means to move to latching position, and said actuating means including means actuatable upon withdrawal of said extensible section from said position to cause the movement of said latch from latching position to permit the further retractive movement of said extensible section.
